(No Model.)

A. W. MORGAN.

GAS AND WATER BOX FOR STREETS.

No. 283,411.

Patented Aug. 21, 1883.

UNITED STATES PATENT OFFICE.

AMOS W. MORGAN, OF BUFFALO, NEW YORK.

GAS AND WATER BOX FOR STREETS.

SPECIFICATION forming part of Letters Patent No. 283,411, dated August 21, 1883.

Application filed September 25, 1882. (No model.)

To all whom it may concern:

Be it known that I, AMOS W. MORGAN, a citizen of the United States, residing at Buffalo, county of Erie, and State of New York, have made certain Improvements in the Construction of Shut-Off Boxes for Gas and Water for Street-Mains and Service-Pipes, of which the following is a specification.

The invention relates to improvements in the construction of cast-iron service-boxes for shutting off and turning on gas or water, either from the street-roadway or sidewalks or other places, and are in connection with my patent for screw extension-boxes, No. 193,829, August 7, 1877; and this invention relates to the pipe (forming part of the whole box) and its connection to an independent base for the same, and improvements in the base, all as hereinafter fully specified.

In the drawings, Figure 1 is a side elevation, partly in section, and showing the pipe-connection with the base; Fig. 2, an elevation of part of a pipe, and Fig. 3 a perspective of the base.

A represents the pipe, having a screw-thread on the upper part to receive the screw-top, (not shown,) the whole making a continuous adjustable service-pipe or "box," which is shown in my former patent, above referred to.

On and around the bottom of pipe A is cast a locking-ring, *a*, in segments, for the purpose of attaching it to the base B. This ring *a* is cast either square or rounded, and with open spaces *b* in the ring, each space opposite the other, dividing the ring into two parts or segments, for the purpose to be presently explained. The upper surface of these rings is made slanting toward the spaces *b*, as shown in Figs. 1 and 2, the apex of the incline being at *a'*, (see Fig. 2,) for the purpose of locking more securely.

The base B is cast of or in a single piece, having a somewhat oval form at the bottom, so as to entirely cover and also protect perfectly the usual valve used under it in water-pipes for turning on or shutting off water or gas. Around the bottom of the base is cast a wide flange, *c*, setting out therefrom at right angles to set flat on the ground, so as to give stability to the whole box, preventing settling on and springing the pipe or valve. This flange is strengthened by several brackets, *dd*,

cast on the base and flange, as shown. The top of the base B is made round, and of a little greater circumference than the pipes, and having a rim, *e*, and a seat or shoulder, *e'* inside said rim for the pipe A to rest on. In addition, and for the purpose of connecting the base and pipe, I cast on lugs *ff*, which project a little from the sides, and also above as shown in Fig. 3. These lugs have a slight recess, *g*, on the inside, sufficient to catch over the locking-ring *a*, as shown in Figs. 1 and 3. The lugs are just wide enough to pass through the openings *b* in the rings, and when the bottom of the pipe rests on the seat *e'* of the base B a turn is given the pipe, and the ring *a* slides in the recess *g* of the lugs *ff*, thus locking it in, the slant in the ring holding it all the tighter. The openings *b* in the rings *a* are so they will meet the lug *ff*. When the whole is set in the ground and filled about with earth, they remain perfectly immovable.

The object of making the base B separate from the pipe is to better handle them both and to aid in setting them true in the ground so as to bring the nut of the valve of the water or gas pipe directly in the center, that it can readily be found by parties desiring to turn on or off the water or gas. Making the pipe A and base B in two pieces avoids the great difficulty of casting both in one piece. Another important feature is casting on the pipes A two or more locking-rings, *aa*. (See Fig. 2.) This is for the purpose of allowing the pipes to be cut into suitable lengths without being set in the ground, the division being made close to a ring *a*, so that after being cut off it can be locked by a ring in the base B. With these screw-pipes it is course impossible to cut them at the top, as if there was only one ring *a* on the pipe when the pipe was shortened there would be no locking-ring left. By casting two or more rings *a* on the pipes a piece can be cut close to a ring and still be fastened to the base B. This is an important feature, as gas and water pipes are set at uneven depths, sometimes more or less than would be provided by my screw-pipe.

I claim—

1. The combination of a pipe, A, of a wa-

ter and gas box, having ring *a* and spaces *b* the

on, with the base B, constructed with the recessed lugs f g and seat e', substantially as and for the purpose specified.

2. The base B of a water and gas box, made in one casting, and having the flange or rim e, recessed lugs f g, and upright rim and seat e e', in combination with the pipe A and segmental ring a, all substantially as and for the purpose specified.
- 10 3. The base B of a water and gas box, cast in one piece and separate from the pipe A, and having the flange or rim e at the bottom,

and rim e and seat e' at the top, and in combination with an upright pipe, A, to be set therein or thereon, substantially as and for the purpose specified.

In witness whereof I have hereunto signed my name in the presence of two subscribing witnesses.

AMOS W. MORGAN.
